CLAIM

The ornamental design for an earphone case, as shown and described.

DESCRIPTION

FIG. 1 is a right front perspective view of a first embodiment of an earphone case showing our new design; FIG. 2 is a front view of the first embodiment; FIG. 3 is a back view of the first embodiment; FIG. 4 is a top view of the first embodiment; FIG. 5 is a bottom view of the first embodiment; FIG. 6 is a right side view of the first embodiment; FIG. 7 is a left side view of the first embodiment; FIG. 8 is a back perspective view of the first embodiment; FIG. 9 is a left front perspective view of the first embodiment in an open state; FIG. 10 is a right front perspective view of the first embodiment in an open state; FIG. 11 is a left front perspective view of the first embodiment in an open state with earphones; FIG. 12 is a right front perspective view of the first embodiment in an open state with earphones; FIG. 13 is a right front perspective view of a second embodiment of an earphone case showing our new design; FIG. 14 is a front view of the second embodiment; FIG. 15 is a back view of the second embodiment; FIG. 16 is a top view of the second embodiment; FIG. 17 is a bottom view of the second embodiment; FIG. 18 is a right side view of the second embodiment; FIG. 19 is a left side view of the second embodiment; FIG. 20 is a back perspective view of the second embodiment; FIG. 21 is a left front perspective view of the second embodiment in an open state; FIG. 22 is a right front perspective view of the second embodiment in an open state;

(Continued)

FIG. 23 is a left front perspective view of the second embodiment in an open state with earphones; and, FIG. 24 is a right front perspective view of the second embodiment in an open state with earphones. The broken lines in drawings show portions of the earphone case that form no part of the claimed design. The oblique line shading in the drawings depicts a highly polished or reflective surface, rather than a transparent surface.
